SIGNAL-GENERATING SYSTEM

Rudolf C. Hergenrother, Beechhurst, N. Y., assignor to Hazeltine Corporation, a corporation of Delaware

Application January 19, 1940, Serial No. 314,573

7 Claims. (Cl. 250—150)

This invention relates to signal-generating systems of the type including a cathode-ray signal-generating tube having a photosensitive target which is scanned by a beam of low-velocity electrons in order to develop a signal output from the cathode-ray tube. While the invention is of general application, it is of particular utility as a video-frequency signal-generating arrangement in a television transmitting system.

Video-frequency signal-generating systems in television transmitters have commonly included a cathode-ray tube having a photosensitive target on which is focused an image of the scene to be transmitted and which is scanned by a beam of electrons to provide at the point of impact at the target a secondary-emission ratio of greater than unit. In such systems, the number of secondary electrons emitted by each incremental area of the target, which electrons are collected continuously by a suitable electron collector as the target is scanned, is determined by the charge of the area, which, in turn, is determined by its intensity of illumination. Such systems generally comprise a suitable backing plate for the photosensitive target electrode from which the video-frequency output of the system is derived. It has also been proposed to derive the video-frequency output of such an arrangement from the current to the electron collector of the cathode-ray tube. However, signal-generating arrangements of the general type described, which utilize a cathode-ray signal-generating tube including a photosensitive target electrode which is scanned by electrons of sufficiently high velocity to provide secondary-electron emission ratio at the target, which is greater than unity, in order to derive a signal output therefrom, are subject to the disadvantage that the relation between the light input to the system and the generated signal output is not linear; that is, the system does not generate a signal with unity gamma. Such systems are also deficient in that some of the secondary electrons which are emitted from the target rain back on the target and impair the charge distribution thus decreasing its sensitivity and causing undesirable shading effects.

It has been proposed also to utilize in a signal-generating system a cathode-ray signal-generating tube having a photosensitive target which is scanned by electrons of such low velocity that the secondary-emission ratio is less than unity, the output signal being taken from a backing plate associated with the photosensitive target. Such an arrangement is effective to eliminate certain of the disadvantages associated with systems utilizing

ing a sufficiently high velocity scanning beam to cause a secondary-electron emission ratio greater than unity at the target. A system utilizing a scanning beam of sufficiently low velocity that fewer secondary electrons are emitted by the target than strike it is disclosed in an article entitled "The Orthicon" in "Electronics" for July 1939.

However, signal generators of either of the types mentioned above provide an output signal, the amplitude of which is so minute as to necessitate a high degree of amplification to procure a useful signal. Such amplification is difficult to produce in conventional vacuum-tube amplifier circuits for the reason that the thermal noises associated with the vacuum tube are comparable in magnitude to the signal to be amplified. Electron multipliers have heretofore been utilized in association with signal-generating cathode-ray tubes having a photosensitive target which is scanned by an electron beam of sufficiently high velocity to provide a secondary-electron emission ratio at the target which is greater than unity, in order to provide a signal output of relatively large amplitude without the disadvantages associated with the use of conventional vacuum-tube amplifier circuits. With such arrangements, it has been proposed to apply to the electron collector associated with the electron multiplier a suitable potential to attract the secondary electrons emitted by the photosensitive target during the scanning operation.

However, in all practical electron multipliers it is necessary to supply the electrons thereto for multiplication within a relatively small area. In prior-art arrangements utilizing cathode-ray signal-generating tubes in which the target is scanned by a low-velocity scanning beam to provide a secondary-electron emission ratio of less than unity, if the collector electrode has a suitably high potential for efficiently collecting electrons from the photosensitive target at a spot of restricted area, such potential would adversely affect the scanning beam. It is particularly desirable, therefore, to provide a cathode-ray signal-generating tube including a photosensitive target which is scanned by electrons of sufficiently low velocity as to provide at the target a secondary-emission ratio of less than unity and which includes an electron collector associated therewith effective to collect electrons at a spot of restricted area thereon and at a rate varying in accordance with the signal to be generated but having substantially no influence on the scanning beam.

It is an object of the invention, therefore, to

provide an improved signal-generating system including a cathode-ray tube having a photosensitive target adapted to be scanned by an electron beam of sufficiently low velocity as to provide a secondary-emission ratio of less than unity at the target.

It is a further object of the invention to provide an improved signal-generating system including a cathode-ray tube having a photosensitive target adapted to be scanned by an electron beam of sufficiently low velocity as to provide a secondary-emission ratio of less than unity and having associated therewith a suitable electron collector adapted to receive from the target an electron beam varying in accordance with the signal to be generated and having substantially no influence on the scanning beam.

In accordance with the invention, a signal-generating system comprises a cathode-ray signal-generating tube having a photosensitive target electrode and an electron collector. Means are provided for developing and accelerating toward the target electrode a beam of electrons of substantially constant intensity and having a velocity which is sufficiently low at the target electrode as to provide a secondary-emission ratio of less than unity and for returning free electrons from the vicinity of the target, together with magnetic means for scanning the target in two directions normal to each other with the beam, whereby the number of electrons returning from the vicinity of each incremental area of the target, as such area is scanned by the beam, is determined primarily by the charge of such area due to an image projected thereon. The returning free electrons travel back through the magnetic means along substantially the same path as that traversed through the magnetic means by the scanning beam. There is also provided means including a pair of beam-shifting plates adjacent the beam-developing means and having a spacing therebetween which is small relative to the scanning deflections of the beam, and means including means for applying a steady unidirectional potential to the beam-shifting plates for directing, as an electron beam to a spot of restricted area on the electron collector, which spot is displaced from the first-named means in a predetermined direction, substantially all of the electrons returning from the vicinity of the target, whereby there is derived an output signal from the electron collector which varies in accordance with the number of electrons directed thereto. At the same time, the potential of the collector electrode and its arrangement in the tube are such that it does not impair the proper deflection of the electron beam.

For a better understanding of the present invention, together with other and further objects thereof, reference is had to the following description taken in connection with the accompanying drawing and its scope will be pointed out in the appended claims.

The single figure of the drawing is a circuit diagram, partly schematic, of a television transmitting system including a video-frequency signal-generating system embodying the present invention.

Referring now more particularly to the drawing, the television transmitting system illustrated includes a conventional camera or projector 10 and a cathode-ray signal-generating unit 11 having associated therewith an electron multiplier 12 which may be of any suitable well-

known construction. Connected in cascade to the output circuit of electron multiplier 12, in the order named, are a video-frequency amplifier and mixer 13, an oscillator-modulator 14, a radio-frequency amplifier 15, and an antenna system 16, 17. The system includes a suitable timing and scanning signal generator 18 from which are derived suitable scanning fields for the signal generator 11 and suitable blanking and synchronizing signals for the transmitted television signal.

The signal generator 11 comprises an evacuated tube or envelope 20 having at one end thereof a suitable cathode or source of electrons 21 which, together with accelerating anodes 23 and 23', comprises an electron gun effective to generate a beam of relatively low-velocity electrons. Anode 23' has a very small aperture therein so that the developed electron beam is of very small cross section. In order to provide a longitudinal magnetic field within the tube 20 effective to direct the electron beam emitted by cathode 21 to a photosensitive target electrode 22 of tube 11, there is provided a winding 19 surrounding the tube 20 and energized from a suitable source, such as a battery 24. Magnetic scanning fields for deflecting the cathode-ray beam in each of two directions normal to each other are provided by scanning windings 25, 25 and 26, 26, respectively, disposed successively along the tube and having their axes normal to each other, as shown in the drawing, or superposed so that one set of windings encloses the other. Target 22 preferably comprises a photosensitive mosaic deposited on a thin insulating sheet 8 on the opposite side of which is a grounded metallic coating or backing plate 9. A grounded metallic coating is provided on the inner surface of the tube between the electron gun and target 22. In order to provide a fixed deflection or offset of the cathode-ray beam, there are provided beam-shifting plates 27, 28 having a fixed potential difference applied therebetween from taps on battery 24. Plates 27, 28 have a spacing therebetween which is small relative to the scanning deflections of the beam. Electron multiplier 12 has an opening adjacent cathode 21 and facing the target 22 in which is disposed an electron collector 29 having an aperture therein and having a suitable potential applied thereto from source 24. Since the camera 10 projects the image to be transmitted on the side of target 22 opposite to that scanned by the electron beam which is the photosensitive surface, the target 22 must be at least semi-transparent.

Neglecting for the moment the operation of the cathode-ray signal-generating unit 11, the apparatus just described comprises the features of a conventional television transmitting system. The construction and operation of such apparatus being well known in the art, a detailed description thereof is deemed unnecessary herein. In brief, however, in the operation of the apparatus, an image of the scene to be transmitted is projected by camera 10 on the photosensitive surface of target electrode 22 in order to develop a video-frequency signal output from electron multiplier 12 which varies in accordance with variations in illumination from point to point of the target as it is scanned. The video-frequency signal output of the electron multiplier 12 is amplified in video-frequency amplifier 13 and mixed therein with the synchronizing signals and the blanking signals to be transmitted.

The composite signal output of the video-frequency amplifier and mixer 13 is utilized to modulate a suitable carrier wave in oscillator-modulator 14, the modulated-carrier signal being thereafter amplified in radio-frequency amplifier 15 and supplied to transmitting system 16, 17 for radiation.

Coming now to the operation of the portion of the system involving the present invention, a beam of electrons of substantially constant intensity and having a velocity which is sufficiently low as to provide a secondary-emission ratio of less than unity at the target electrode 22 is directed thereto by means of the magnetic field developed by winding 19. In the absence of all deflecting potentials, such electron beam would follow in a tight spiral the lines of force of the winding 19 from the aperture in accelerating anode 23' to the target electrode 22. The accelerating anodes 23 and 23', having apertures therein, are, therefore, included in a means for accelerating as well as in a means for developing and accelerating toward the target electrode 22 a beam of electrons which is perpendicular to the plane of the target. Under the influence of 15 the magnetic scanning fields provided by coils 25 and 26, however, the beam is first deflected in one direction by means of the field developed by windings 25, 25 and is then deflected in another direction at right angles thereto by means of the field developed by windings 26, 26 and is thus effective to scan the target electrode 22 in a field or series of parallel lines.

Neglecting the action of beam-shifting plates 27, 28, the electron beam from the aperture in the accelerating anode 23' is deflected in two directions normal to each other and is at all times incident upon target electrode 22 substantially perpendicular thereto so as to prevent defocusing of the beam. The operating potentials 20 of the tube are so adjusted that the velocity of the scanning beam is very small near the surface of target electrode 22; that is, so that the secondary-electron emission ratio from target 22 is less than unity. Under these conditions, and 25 under a condition of equilibrium when none of the electrons of the scanning beam is utilized to neutralize a charge on the target, the target is substantially at the potential of the cathode. When the target is thus at cathode potential, 30 electrons from the beam approaching the target normal to its surface will be brought to rest just at the target surface by the electric field and then will return by the same path to the aperture in collector electrode 23' under the influence of 35 the electric field. That is, the returning free electrons travel back through the magnetic means along substantially the same path as that traversed through the magnetic means by the scanning beam. The electron beam follows the magnetic lines of force of the combined focus and scanning field both in its travel toward the target and in its return from the target and since the time of this travel is so small that no appreciable change occurs in the scanning field in this interval, the beam returns to substantially its starting point. If there is a positive charge on the portion of photosensitive target 22 upon which the beam is incident due to photoelectric emission from such area that portion will effectively retain a sufficient number of electrons from the beam to neutralize the charge, thereby correspondingly diminishing or modulating the intensity of the return beam.

In accordance with the invention, however,⁷⁵

there is provided a suitable deflecting potential upon plates 27 and 28 which is effective to displace the electron beam coming from cathode 21 in a given direction parallel to plates 27 and 28, as illustrated by the arrows *a*, and to effect a displacement of the returning cathode-ray beam, as illustrated by the arrows *b*, so that the resultant over-all lateral displacement can be made equal to the distance between cathode 21 and the aperture in electron collector 29, which are adjacently positioned. That is, the beam-shifting plates 27, 28 provide a constant electrostatic field perpendicular to the longitudinal magnetic field provided by winding 19 and perpendicular to a plane through the centers of the source 21 and the electron collector 29. The electron collector is of a restricted area. Therefore, the returning electrons are directed to the aperture in the electron collector 29 of electron multiplier 12 after which electron multiplication may be effected in conventional manner. That is, a means is provided for directing, as an electron beam to a spot of restricted area on the electron collector 29, substantially all of the electrons which leave the target 22 and, inasmuch as the number of electrons which return from the vicinity of each incremental area of the target 22 as such area is scanned by the beam is determined only by the charge of such area, the intensity of the returning electron beam at electron collector 29 varies in accordance with variations of illumination of the successive incremental areas of the target 22 and is representative of the signals to be generated. At the same time the shading effects and lack of sensitivity accompanying the use of a scanning beam of sufficiently high voltage to produce a secondary-electron emission ratio of greater than unity at the target are avoided while the potential of the collector electrode 29 approximates that of anode 23' so that its effect on the scanning beam is negligible.

While there has been described what is at present considered to be the preferred embodiment of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A signal-generating system comprising, a cathode-ray signal-generating tube having a photosensitive target electrode and an electron collector, means for developing and accelerating toward said target electrode a beam of electrons of substantially constant intensity and having a velocity which is sufficiently low at said target electrode as to provide a secondary-emission ratio of less than unity and for returning free electrons from the vicinity of said target, magnetic means for scanning said target in two directions normal to each other with said beam, whereby the number of electrons returning from the vicinity of each incremental area of said target as such area is scanned by said beam is determined primarily by the charge of such area due to an image projected thereon and such returning free electrons travel back through said magnetic means along substantially the same path as that traversed through said magnetic means by said scanning beam, means including a pair of beam-shifting plates adjacent said beam-developing

means and having a spacing therebetween which is small relative to the scanning deflections of said beam, and means including means for applying a steady unidirectional potential to said beam-shifting plates for directing as an electron beam to a spot of restricted area on said electron collector, which spot is displaced from said first-named means in a predetermined direction, substantially all of the electrons returning from the vicinity of said target, whereby an output signal may be derived from said electron collector which varies in accordance with the number of electrons directed thereto.

2. A signal-generating system comprising, a cathode-ray signal-generating tube having a photosensitive target electrode and an electron collector, means for developing and accelerating toward said target a beam of electrons of substantially constant intensity, which is perpendicular to the plane of said target, which has a velocity which is sufficiently low at said target electrode as to provide a secondary-emission ratio of less than unity, and for returning free electrons from the vicinity of said target, magnetic means for scanning said target electrode in two directions normal to each other with said beam, whereby the number of electrons returning from the vicinity of each incremental area of said target as such area is scanned by said beam is determined primarily by the charge of such area due to an image projected thereon and such returning free electrons travel back through said magnetic means along substantially the same path as that traversed through said magnetic means by said scanning beam, means including a pair of beam-shifting plates adjacent said beam-developing means and having a spacing therebetween which is small relative to the scanning deflections of said beam, and means including means for applying a steady unidirectional potential to said beam-shifting plates for directing as an electron beam to a spot on said electron collector, which spot is displaced from said first-named means in a predetermined direction, substantially all of the electrons returning from the vicinity of said target, whereby an output signal may be derived from said electron collector which varies in accordance with the number of electrons directed thereto.

3. A signal-generating system comprising, a cathode-ray signal-generating tube having a photosensitive target electrode, an electron collector of a restricted area and a source of electrons adjacent said collector, means for accelerating toward said target electrode a beam of electrons from said source of substantially constant intensity and having a velocity which is sufficiently low at said target electrode as to provide a secondary-emission ratio of less than unity and for returning free electrons from the vicinity of said target, magnetic means for scanning said target in two directions normal to each other with said beam, whereby the number of electrons returning from the vicinity of each incremental area of said target as such area is scanned by said beam is determined primarily by the charge of such area due to an image projected thereon and such returning free electrons travel back through said magnetic means along substantially the same path as that traversed through said magnetic means by said scanning beam, means including a pair of beam-shifting plates adjacent said accelerating means and having a spacing therebetween which is small relative to the scanning deflections of said beam,

and means including means for applying a steady unidirectional potential to said beam-shifting plates for directing as an electron beam to a spot of restricted area on said electron collector, which spot is displaced from said first-named means in a predetermined direction, substantially all of the electrons returning from the vicinity of said target, whereby an output signal may be derived from said electron collector which varies in accordance with the number of electrons directed thereto.

4. A signal-generating system comprising, a cathode-ray signal-generating tube having a photosensitive target electrode, means for developing and accelerating toward said target electrode a beam of electrons of substantially constant intensity and having a velocity which is sufficiently low at said target electrode as to provide a secondary-emission ratio of less than unity and for returning free electrons from the vicinity of said target, magnetic means for scanning said target electrode in two directions normal to each other with said beam, whereby the number of electrons returning from the vicinity of each incremental area of said target as such area is scanned by said beam is determined primarily by the charge of said area due to an image projected thereon and such returning free electrons travel back through said magnetic means along substantially the same path as that traversed through said magnetic means by said scanning beam, an electron multiplier associated with said tube and including an electron collector, means including a pair of beam-shifting plates adjacent said beam-developing means and having a spacing therebetween which is small relative to the scanning deflections of said beam, and means including means for applying a steady unidirectional potential to said beam-shifting plates for directing as an electron beam to a spot of restricted area on said electron multiplier for multiplication therein, which spot is displaced from said first-named means in a predetermined direction, substantially all of the electrons returning from the vicinity of said target electrode, whereby an output signal may be derived from said electron multiplier which varies in accordance with the number of electrons directed thereto.

5. A signal-generating system comprising, a cathode-ray signal-generating tube having a photosensitive target electrode and a source of low-velocity electrons therein, means for developing and accelerating toward said target electrode a beam of electrons from said source of substantially constant intensity which has a velocity sufficiently low at said target electrode as to provide a secondary-emission ratio of less than unity and for returning free electrons from the vicinity of said target, magnetic means for deflecting electrons from said source in two directions normal to each other to scan said target with said beam, whereby the number of electrons returning from the vicinity of each incremental area of said target as such area is scanned by said beam is determined primarily by the charge of such area due to an image projected thereon and such returning free electrons travel back through said magnetic means along substantially the same path as that traversed through said magnetic means by said scanning beam, an electron collector, means including a pair of beam-shifting plates adjacent said beam-developing means and having a spacing therebetween which is small relative to the scanning de-

lections of said beam, and means including means for applying a steady unidirectional potential to said beam-shifting plates for directing as an electron beam to a spot of restricted area on said electron collector, which spot is displaced from said first-named means in a predetermined direction, substantially all of the electrons returning from the vicinity of said target, whereby an output signal may be derived from said electron collector which varies in accordance with the number of electrons directed thereto.

6. A signal-generating system comprising, a cathode-ray signal-generating tube having a photosensitive target electrode and an electron collector, a source of low-velocity electrons in said tube, means for accelerating toward said target a beam of electrons from said source of substantially constant intensity and for returning free electrons from the vicinity of said target, the electrons of said beam having a velocity which is sufficiently low at said target electrode as to provide a secondary-emission ratio of less than unity, means for developing a longitudinal magnetic field between said source and said target electrode, magnetic means for deflecting electrons from said source in two directions normal to each other to scan said target with said beam, whereby the number of electrons leaving each incremental area of said target as such area is scanned by said beam is determined primarily by the charge of such area due to an image projected thereon and such returning free electrons travel back through said magnetic means along substantially the same path as that traversed through said magnetic means by said scanning beam, means including a pair of beam-shifting plates adjacent said accelerating means and having a spacing therebetween which is small relative to the scanning deflections of said beam, and means including means for applying a steady unidirectional potential to said beam-shifting plates for directing as an electron beam to a spot of restricted area on said electron collector, which spot is displaced from said source of electrons in a predetermined direction, substantially all of the electrons returning from the vicinity of said

target, whereby an output signal may be derived from said electron collector which varies in accordance with the number of electrons directed thereto.

- 5 7. A signal-generating system comprising, a cathode-ray signal-generating tube having a photosensitive target electrode, an electron collector, and a source of electrons adjacent said collector, means for accelerating toward said target electrode a beam of electrons of substantially constant intensity which has a velocity sufficiently low at said target electrode to provide a secondary-emission ratio of less than unity and for returning said beam to the vicinity of said source of electrons, means for developing a longitudinal magnetic field between said source and said target electrode, means including a pair of beam-shifting plates adjacent said accelerating means and having a spacing therebetween which is small relative to the scanning deflections of said beam, and means for applying a steady unidirectional potential to said beam-shifting plates for providing a constant electrostatic field perpendicular to said magnetic field and perpendicular to a plane through the centers of said source and said electron collector, and magnetic means for deflecting said beam in two directions normal to each other to scan said target, whereby the number of electrons returning from the vicinity of each incremental area of said target as such area is scanned by said beam is determined primarily by the charge of such area due to an image projected thereon and such returning free electrons travel back through said magnetic means along substantially the same path as that traversed through said magnetic means by said scanning beam, said electron source and said electron collector being spaced by such a distance that substantially all of the electrons which return from the vicinity of said target are directed as an electron beam to a spot of restricted area on said electron collector, whereby an output signal may be derived from said electron collector which varies in accordance with the number of electrons directed thereto.

RUDOLF C. HERGENROTHER.
